DESIGN FOR A COMBINED ELECTRIC CLEANER AND POLISHER

Gustave J. Soderberg, Babylon, N. Y.

Application October 5, 1944, Serial No. 115,633

Term of patent 14 years

(Cl. D9—2)

To all whom it may concern:

Be it known that I, Gustave J. Soderberg, a citizen of the United States, residing in the city of Babylon, county of Suffolk, and State of New York, have invented a new, original, and ornamental Design for a Combined Electric Cleaner and Polisher, of which the following is a specification, reference being had to the accompanying drawings, forming a part thereof.

Figure 1 is a side view of a combined electric cleaner and polisher, showing my design.

Fig. 2 is a top plan view of the polisher;

Fig. 3 is a rear view thereof.

I claim:

The ornamental design for a combined electric cleaner and polisher, as shown.

GUSTAVE J. SODERBERG.
